UNITED STATES PATENT OFFICE

FRANK JEROUSEK, OF BALTIMORE, MARYLAND

DRIP CATCHER FOR PAINT BRUSHES AND THE LIKE

Application filed June 22, 1932. Serial No. 618,754.

The invention relates to an attachment for paint brushes and the like to catch the paint or other material dripping from the brush to prevent soiling the hands of the painter 5 and to prevent waste of the paint or other material and has for its principal object the provision of a device made of rubber or other yieldable material that is adapted to be mounted on the brush head and retained 10 thereon by frictional engagement of the attachment and having an integral receptacle formed thereon the walls of which surround the base of the brush bristles so that the paint or other material caught in the receptacle will be automatically fed back to the brush bristles at their base and prevent waste thereof.

Another object of the invention is the provision in a device of the character stated of 20 inwardly extending flanges on the walls of the receptacle that are inclined inwardly and toward the base of the receptacle and prevent material that may be therein from running out when the brush is lying on its side.

25 A further object of the invention is the provision in a device of the character stated of rods connecting opposite walls of the receptacle and adapted to engage and support the brush bristles when the device is lying on its side and direct material running from the bristles into the receptacle.

The invention will be described in detail hereinafter and will be found illustrated in the accompanying drawing in which

35 Figure 1 is a view in elevation of a paint brush showing my attachment applied thereto,

Figure 2 is a fragmentary view of the brush and the attachment shown in section,

40 Figure 3 is a transverse sectional view on a plane indicated by the line 3-3 of Figure 2, and

Figure 4 is an end view of the attachment.

45 In the drawing similar reference characters are used to designate corresponding parts in all of the views.

A brush handle 10 is shown in Figure 1 and having a head 11 thereon in which are secured the brush bristles 12 in any suitable 50 manner.

The attachment is shown in the drawing and is preferably made of rubber or other yielding material so that it may be applied to and removed from the brush head 11, said attachment having a reduced tubular portion 55 13 to be stretched over said head 11 and to snugly engage it to hold the attachment in position. Surrounding the base of the bristles 12 are expanded walls 14 forming a receptacle at the base of the brush bristles 12 to catch drip therefrom when the brush is used with the bristles 12 uppermost, as when painting a ceiling or the upper portion of a wall or other overhead work. Extending inwardly of the walls 14 are integral flanges 60 15, that, as shown in Figures 2 and 3 incline inwardly of the receptacle and toward the brush bristles thus providing a recess around the walls 14 and between said walls and the flanges 15 to prevent the paint or other material that may be in the receptacle from 65 running out when the brush is laid on its side.

70 Interiorly of the edges of the flanges 15 are rods 16 that are secured in the opposite walls of the receptacle, and may be made of a heavy grade of wire or any other suitable material, and designed to support the brush bristles when the brush is laid on its side, and also to discharge paint or other 75 material that may run down the bristles when in such position into the receptacle.

What is claimed is:—

1. A drip catcher for paint brushes, comprising a tubular member adapted to surround and closely engage a brush head, said tubular member having an enlarged tubular portion at one end thereof and having oppositely disposed walls offset therefrom, said enlarged portion being adapted to surround brush bristles in said head and adapted to catch drippings from the bristles, and rods secured in opposite walls of said enlarged portion and adapted for location on opposite sides of the bristles to support them when the brush head and bristles are lying on one side and direct drip onto said enlarged portion.

2. A drip catcher for paint brushes as in claim 1, in which the tubular member and

enlarged portion is constructed of elastic material, and the edge of said enlarged portion is provided with an inturned flange to prevent escape of drippings therefrom.

- 5 3. In combination with a brush having a head and bristles secured therein, a tubular member mounted on the head and having an outwardly offset portion provided with oppositely disposed walls surrounding said
- 10 bristles and forming therewith a receptacle to catch drippings therefrom, and rods secured in opposite walls of the offset portion and on opposite sides of the brush bristles to limit the movement of the bristles and to
- 15 support them when the brush is lying on a side, and an inturned flange around the edge of said enlarged portion to direct drippings into the receptacle and escape therefrom.

In testimony whereof I affix my signature.
20 FRANK JEROUSEK.
